UNITED STATES PATENT OFFICE

2,153,369

ELECTRIC SWITCH

Frank C. De Reamer, Bridgeport, Conn., assignor
to General Electric Company, a corporation of
New York

Original application July 29, 1936, Serial No.
93,237. Divided and this application Septem-
ber 9, 1937, Serial No. 163,089

8 Claims. (Cl. 200—159)

The present invention relates to push button operated electric switches. This application is a division of my application Serial Number 93,237, filed July 29, 1936.

5 The object of my invention is to provide an improved construction and arrangement in switches of this type, and, for a consideration of what I believe to be novel and my invention, attention is directed to the accompanying description and the claims appended thereto.

In the accompanying drawing, Fig. 1 is a side elevation of an electric switch embodying my invention; Fig. 2 is a sectional elevation taken on line 2—2 of Fig. 1; Fig. 3 is an exploded view of 15 the switch; Fig. 4 is a bottom plan view of the switch; and Fig. 5 is a sectional elevation of a modification.

Referring to the drawing, I have shown my invention applied to a switch having a housing 1 of molded insulating material having bosses 2 at opposite sides thereof. In the upper faces of the bosses are recesses 3 for receiving terminals 4 which comprise V-shaped metal strips with the sides 5 of the V pressed tightly together. At 25 the junction of the sides of the V the terminals are provided with openings through which extend the bared ends 6 of stranded line conductors 7. With this arrangement the bared ends of the conductors are fanned out and forced into firm electrical contact with the sides 5 of the terminals when the sides of the terminals are clamped together. The terminals are held in the recesses 3 by projections 8 on the terminals which fit into depressions 9 in the recesses. The upper end 30 of the housing is closed by a sheet or member 10 of insulating material which is provided with ears 11 extending over the bosses 2. When the member 10 is secured to the top of the housing, the ears 11 clamp the terminals securely in the 35 recesses 3 and also increase the clamping effect of the sides of the terminals on the bared ends of the conductors thereby providing a connection between the terminals and the conductors which does not require soldering. The member 10 is secured to the top of the housing by a metal plate 12 having tangs 13 which are bent over a bead 14 at the top of the housing. As shown in Figs. 1 and 4, tangs 13 engage the sides of the bosses 2 and locate the metal plate 12 on top 40 of the housing. The tangs 13 also extend on either side of the ears 11 and thereby prevent turning of the member 10 with respect to the housing. The conductors 7 are supported by an arm 12a on the plate 12. The conductors are first drawn tightly against the switch housing

and are secured to the arm 12a by ears 12b which are folded over the conductors. The metal plate 12 is secured to the lower end of a threaded sleeve 15 by spun-over portions 16. The switch may be mounted by extending the sleeve through 5 a support and by clamping the support between nuts 17 threaded on the sleeve.

In the sleeve 15 is a push button which comprises a drawn tubular metal shell 18, the closed end of the shell projecting beyond the sleeve 15 where it may be engaged by the operator, and the tubular body portion of the shell being slidable 10 in the sleeve. Within the shell 18 is an operating rod 19 which is secured therein by a washer 20 pressed or wedged into the shell and held 15 therein by frictional engagement of the edges of the washer and the adjacent walls of the shell. The operating rod has a head 21 which provides a shoulder 22 co-operating with the washer to hold the operating rod in place. The lower end 20 of the operating rod is guided in an opening 23 in the member 10. There is sufficient clearance between the washer and the operating rod, and between the head 21 of the operating rod and the end of the shell 18, so that the operating rod 25 may have a limited angular movement in the shell, or, viewed from another aspect, the operating rod is free to swivel in the push button. The swiveling of the operating rod prevents binding of the operating rod in the guiding opening 30 23 in case the member 10 is assembled so that this opening is not in exact alignment with the operating rod. The operating rod 19 projects below the member 10 and the projecting end is provided with a reduced portion 24 on which is 35 loosely carried a washer 25 of insulating material. The washer 25 is held in place by turning over the end of the operating rod to form a flange so that the washer fits loosely between the flange and the shoulder at the upper end of 40 the reduced portion 24. Around the periphery of the washer is a metal rim 26 which serves as a bridging contact which co-operates with the inner ends of terminals 4 to complete an electric circuit between the terminals. 45

The push button is biased to the outer position shown in Fig. 2 by a coil spring 27 which is arranged around the operating rod and between the member 10 and the washer 20. The spring biases the push button outwardly so that the 50 metal rim 26 is normally held against the terminals 4 to complete a circuit between the terminals. There is sufficient clearance between the washer 25 and the groove 24 so that the metal rim 26 can align itself with the terminals and thereby 55

provide uniform contact with the terminals. The circuit between the terminals is broken by pushing the push button inward.

The switch shown in Figs. 1 to 4, inclusive, is 5 of the type in which the circuit through the switch is normally closed. In Fig. 5 is shown a modification of the switch in which the circuit through the switch is normally open.

The construction of the switch shown in Fig. 10 5 is identical with the switch shown in Figs. 1 to 4, inclusive, except for the construction of the terminals, the stationary contacts and the push button and the identical parts are indicated by the same reference numerals. The terminals 15 comprise angular metal strips 30, the upper ends of which fit within the depressions 3, and the lower ends of which serve as solder lugs which are soldered to the bared ends 6 of the line conductors 1. The upper ends of the strips 30 are 20 secured to contacts 31 which fit in grooves 32 in the switch housing. At the bottom the contacts are provided with a stepped portion 33 which is arranged to co-operate with the contact 26 on the lower end of the operating rod 19. Between 25 the head 21 of the operating rod and the end of the shell 18 is a coil spring 34. This spring normally holds the shoulder 22 of the operating rod against the washer 20, but permits the operating rod to move upwardly in the push 30 button when the resistance offered to further movement of the operating rod exceeds the tension of the spring. The push button is normally held in the position illustrated by the coil spring 27 which is arranged between the member 10 and 35 the washer 20. In this position the contact 26 is held against the underside of the member 10 and the circuit between the contacts 31 is open. When the push button is pushed inward the contact 26 is moved into engagement with the stepped portions 33 of the contacts 31, thereby completing the circuit between the contacts. During the initial movement of the push button the spring 34 is not compressed and the operating rod occupies the position in the push button illustrated. As soon as the contact pressure between the contacts 26 and 33 exceeds the tension of the spring 34 the operating rod moves upwardly with respect to the push button. The spring 34, therefore, provides a cushion between the operating 40 rod and the push button, which limits the contact pressure between the contacts 26 and 33.

What I claim as new and desire to secure by Letters Patent of the United States, is:

1. In an electric switch, a push button having 55 a tubular body, a washer secured therein, an operating rod slidably projecting through said washer and having a shoulder thereon cooperating with said washer to hold the rod in the push button, and a spring between the operating rod 60 and the push button for holding said shoulder against said washer and for providing a cushion between the push button and the operating rod.

2. In an electric switch, a housing having a 65 tubular sleeve, a push button having a tubular body slidable in said sleeve, a washer fixed in the body of said push button, an operating rod projecting through said washer and extending beyond said push button, a shoulder on said rod 70 cooperating with said washer to hold the rod in the push button, guiding means for the operating rod, said operating rod having a loose fit in said washer permitting a limited angular movement with respect to the push button whereby binding of the guiding rod in its guiding means is decreased, and a coil spring arranged around said

operating rod and extending within the body of the push button for biasing the push button outward.

3. In an electric switch, a housing, a tubular sleeve secured to said housing, a member of insulating material clamped between said sleeve and said housing, a push button having a tubular body slidable in said sleeve, an operating rod secured in said push button and projecting through a guiding opening in said member, and a coil spring around said operating rod extending within the tubular body of the push button and engaging said member for biasing said push button outward.

4. In an electric switch, a housing, a tubular sleeve secured to said housing, a member of insulating material clamped between said sleeve and said housing, a push button having a tubular body slidable in said sleeve, a washer secured in said tubular body, an operating rod projecting through said washer and through a guiding opening in said member, a shoulder on said rod cooperating with said washer to hold the rod in the push button, said operating rod having a loose fit in said washer permitting a limited angular movement with respect to the push button whereby binding of the guiding rod in said guiding opening is decreased, and a coil spring around said operating rod arranged between said washer and said member for biasing the push button outward.

5. In an electric switch, a housing, a tubular sleeve secured to said housing, a member of insulating material clamped between said sleeve and said housing, a push button having a tubular body slidable in said sleeve, a washer secured in said tubular body, an operating rod slidably projecting through said washer and through a guiding opening in said member, a shoulder on said rod cooperating with said washer to hold the rod in the push button, said rod having a loose fit in said washer permitting a limited angular movement with respect to the push button whereby binding of the guiding rod in said guiding opening is decreased, and a spring between the operating rod and the push button for holding said shoulder against said washer and for providing a cushion between the push button and the operating rod.

6. In an electric switch, a housing, a tubular sleeve secured to the housing, a member of insulating material clamped between the sleeve and the housing, a push button slidable in the sleeve having an operating rod projecting through a guide opening in said member, and a coil spring around said operating rod and engaging said member for biasing the push button outward.

7. In an electric switch, a housing of insulating material open at one end, a member of insulating material over the open end of the housing, a metal plate secured to the housing and clamping said member in place, a tubular sleeve secured to said plate, a push button slidable in said sleeve and having an operating rod projecting through a guide opening in said member, and a coil spring around said operating rod and engaging said member for biasing the push button outward.

8. In an electric switch, a housing, including a member of insulating material having an opening therein, a push button mounted on said housing and having an operating rod projecting through and guided in said opening, and a coil spring around the operating rod and engaging said member for biasing the push button outward.
